UNITED STATES PATENT OFFICE.

BENJAMIN F. OREWILER, OF CHICAGO, ILLINOIS.

ADJUSTING-BUCKLE.

1,249,812.

Specification of Letters Patent. Patented Dec. 11, 1917.

Application filed April 21, 1916. Serial No. 92,605.

To all whom it may concern:

Be it known that I, BENJAMIN F. OREWILER, a citizen of the United States, residing at Chicago, in the county of Cook and State of Illinois, have invented certain new and useful Improvements in Adjusting-Buckles, of which the following is a specification.

The present invention relates to a buckle for enabling the adjustment of the length of a suspending strap, and is of the general type of buckle shown and described in my issued Patent No. 1,193,050, granted August 1, 1916, for adjusting buckles.

The objects of the present invention are, to construct a buckle of the type above referred to, which will require a relatively small amount of metal for the production thereof, thus reducing the cost of manufacture, and which will be of a narrow elongated character, possessing an attractive appearance when placed upon the webbing; to arrange suitable spring-catch members for holding the back and lever portions of the buckle together, and thus hold the buckle in closed position; and to provide a buckle which will be easy and practical of use with various thicknesses of fabric and having a fabric-covering for the back thereof provided.

The invention further consists in the features of construction and combination of parts hereinafter described and claimed.

In the drawings:

Figure 1 is a front view of a portion of a garter with the buckle of the present invention applied thereto;

Fig. 2, a vertical section, showing the buckle in open position;

Fig. 3, a view similar to Fig. 2, showing the buckle in closed position;

Fig. 4, a perspective showing the buckle in closed position; and

Fig. 5, a perspective showing the buckle in open position.

In the art to which the present invention relates, there are certain points which must be present in order to provide a buckle which is of practical commercial merit. Among these are, first, to arrange the buckle so as to have the webbing with which it is used form a fabric covering for the back; second, to arrange the clamping member so that it will easily and efficiently operate with either a thin webbing or a thick webbing, since the webbing with which these buckles are

used, varies considerably in thickness; and, third, to apply the webbing to the buckle in a manner whereby stitching is eliminated, which is detrimental, in that it may sever the elastic cords of the elastic webbing, so that they will shrivel and destroy the elasticity of the webbing.

The buckle of the present invention has all of the above-stated features, as will be apparent from the following description.

Referring now to the drawings, the buckle is shown as applied to an elastic webbing 6, which is looped at its lower end to receive an attachment 7 joined to a hose-supporter clasp 8. The parts 7 and 8 can, of course, be of any suitable construction, and the subject-matter of the present invention is entirely independent of the construction of these parts.

The buckle which forms the subject-matter of the invention consists of a back 9 and a front or lever portion 10. The back is formed with a single horizontal slot 11, providing an upper rail 12 and a lower rail 13, with side rails 14 connecting the upper and lower rails. The lower end 15 of the back, in the construction shown, is bent rearwardly and upwardly to form a U-shaped slot 16 on the rear of the back, into which slot is entered one end 17 of the webbing 6, and when the bent portion is swaged inward, it clamps and retains the webbing end, forming a means for securing the webbing to the back of the buckle. This webbing passes from said slot over the upper edge of the portion 16 (see Figs. 2 and 3), thence downwardly and back upon itself to form a loop 18, thence in front of the lower bar 13, thence through the slot 11, and to the rear of the upper bar 12, and thence on upward.

By referring now to Figs. 2 and 3, it will be apparent that this arrangement provides a fabric covering for the rear of the buckle, which, as stated is one of the points necessary for a commercially practical buckle of this character. The lever member is formed at its upper end with companion loops 19, one on each side (see Figs. 1, 4 and 5). These loops are bent around the upper bar 12 (see Figs. 2 and 3), whereby a hinged connection is provided between the back and lever member; and at the upper end of the lever member is formed a web-engaging portion 20, which consists, as shown, of a plurality of tines or points, which are bent to extend inwardly and downwardly.

It has previously been explained how the webbing passes through the slot 11, and by referring to Fig. 3, it will be seen that in passing through said slot a crimp is formed 5 in the webbing. When the buckle is closed, as in Fig. 3, it will be seen that the acting ends of the web-engaging portion 20 reaches approximately to the position which the fabric assumed when initially threaded through 10 the buckle; that is, this web-engaging portion performs no positive forcing or clamping action upon the webbing. It does not act to deflect the webbing to the rear of the buckle, but simply rests in a position to engage 15 the outer face of the webbing without distorting the webbing from the position it initially assumed when threaded. This is an important feature, since when strain is placed upon the buckle, the webbing will 20 assume substantially the same relation to the front of the buckle, whether it be thick or thin, and the relation so assumed will bring the outer surface of the webbing into engagement 25 with the ends of the web-engaging portion 20, so that these ends will catch the surface of the webbing and resist and check any sliding of the webbing through the buckle. And, owing to the fact that no forcing 30 of the webbing is produced by this web-engaging part of the lever, it is obvious that the buckle is as easily closed and opened with a thin fabric as with a thick.

Owing to the fact that no positive clamping 35 action is exerted by the web-engaging portion, it is necessary to provide some means for holding the lever and back portion of the buckle together and maintain the buckle in closed position; and to bring this about, I provide spring members or fingers 40 21, one on each side of the lower end of the lever portion (see Figs. 4 and 5), and when the buckle is closed these fingers or catches snap over the lower ends 22 of the sides of the back of the buckle, providing a spring- 45 catch connection between the lever portion

and back for holding the buckle in closed position. When strain is exerted upon the webbing, the action of the strain will tend to throw the lever member toward the back, and this strain will therefore assist in maintaining the buckle in closed position. 50

The operation of the device is thought to be clear from the foregoing and a detailed description thereof need not be entered into.

I claim:

A buckle comprising a back portion and a lever portion, said back portion being formed with a straight front section having a single horizontally extending slot therein providing an upper rail, a lower rail, and side rails therebetween, the lower end of said front section being bent rearwardly and upwardly to provide a U-shaped slot to receive and retain one end of the webbing, the upper edge of said bent back portion being approximately in alignment with the lower wall of said slot, said webbing extending across the upper edge of the bent back portion, thence downwardly along the rear of said portion, thence back upon itself to form 70 a loop, thence in front of the bottom rail, thence through the slot to the rear of the back, whereby a fabric covering for the back is produced, said lever member being hinged to the upper bar, a web-engaging member at 75 the upper portion of the lever member, said engaging member when the buckle is closed reaching approximately to the position initially assumed by that part of the webbing which it engages, and a spring-catch connection between the lever portion and the sides of the back for holding the buckle closed, said lever portion being bent intermediate its joined and free ends to cause 80 said free end to extend outwardly and accommodate itself to the threaded fabric when the buckle is closed, substantially as described. 85

BENJ. F. OREWILER.
